UNITED STATES PATENT OFFICE.

ALFRED C. MOORE AND SAMUEL McLAUGHLIN, OF LOS ANGELES,
CALIFORNIA.

PHOTOGRAPHIC-PRINTING FRAME.

SPECIFICATION forming part of Letters Patent No. 573,521, dated December 22, 1896.

Application filed August 29, 1895. Serial No. 560,931. (No model.)

To all whom it may concern:

Be it known that we, ALFRED C. MOORE, a citizen of the United States, and SAMUEL McLAUGHLIN, a subject of the Queen of Great Britain, both residing at Los Angeles, in the county of Los Angeles and State of California, have invented a new and useful Contact-Printing Frame, of which the following is a specification.

10 Our invention relates more particularly to printing-frames for use in photoengraving, in which it is necessary to obtain absolute contact between the negative and the sensitized-metal plate on which the image is to be printed. A very great pressure is necessary in order to give the perfect contact which is essential, and great care is required in the ordinary practice of the art with the printing devices in common use to avoid breaking the 15 negative by uneven pressure upon different parts thereof. In using the ordinary printing devices another difficulty arises in that it is necessary with them to place the sensitized-metal plate over the negative, and it is impossible to note the position of the negative under such plate. Frequently by the old method it would occur that the image would be printed in a very undesirable position on the plate.

The object of our invention is to overcome 20 these objections and to provide means whereby an unskilled operator can easily and quickly place the negative and plate in exact position and apply the powerful pressure required evenly throughout the entire image, 25 and thus produce the absolute contact necessary without any danger of breaking the negative.

Our invention is to be distinguished from those contact-printing frames which are 30 adapted to print a succession of images on a flexible strip which is moved across the negative for that purpose.

Although our invention is adapted for printing upon sensitized paper and other flexible 35 material, it is specially adapted to afford great facility for adjusting the negative and the sensitized-metal plate with relation to each other for photoengraving.

Our invention differs from all other photographic-printing frames in that its hinged 40 lid is transparent and the transparent plate

thereof is arranged to be fastened in the path through which the negative-clamping appliance of the device is adapted to move the negative, so that in practical operation a sensitized plate can be first laid on the bed therefor, then the transparent negative placed thereon, then the transparent plate brought down upon and clamped onto the negative, and then the sensitized plate and negative 55 can be forced up against the transparent plate.

An object of our invention is to provide means whereby the bed-plate and the transparent-glass plate will adjust themselves into 60 parallel positions.

Our invention comprises a contact-printing frame composed of a suitable bed provided with a movable bed-plate adapted to receive the sensitized-metal plate, a movable transparent plate adapted to fit above the bed-plate, means for holding the bed and the glass plate relatively stationary, and means for moving the bed-plate toward the glass plate. By this appliance we make it possible 70 to reverse the order of operation and to place the negative upon the sensitized-metal plate instead of placing the plate upon the negative, as with the old-style contact-printing frames. This enables the workman to see 75 the plate through the negative while placing them together preparatory to printing.

The means which we have invented for moving the bed-plate will be hereinafter fully described; but we regard our invention as 80 embracing, broadly, the combination of the bed, the movable bed-plate mounted on the bed and adapted to receive a sensitized-metal plate and negative and to move them through a determined path, a movable transparent 85 plate adapted and arranged to be fastened in the said path through which the bed-plate is adapted to move the negative, means for fastening the transparent plate in such path, and any suitable means adapted and arranged 90 to move the bed-plate in such path and to push it up sufficiently to force the sensitized plate against the negative and the negative against the transparent plate, and to thus cause perfect contact between the sensitized 95 plate and the negative after the negative has been placed on top of the sensitized plate and 100

the transparent plate has been fastened in place to intercept and hold the negative when the sensitized plate is forced up against it.

Our invention also comprises various combinations and parts hereinafter specified.

Figure 1 is a perspective fragmental view of our newly-invented contact-printing frame, a portion being broken away to expose the construction. Fig. 2 is a reduced rear elevation. Fig. 3 is a vertical section through the printing-frame along the axis of one of the wedges. (See line 3 3, Figs. 4 and 5.) Fig. 4 is a vertical mid-section of the printing-frame through the pivots of the glass-plate frame. (See line 4 4, Figs. 2, 3, and 5.) A negative and a sensitized-metal plate are shown. Fig. 5 is a fragmental plan with the glass-plate frame thrown back and the bed-plate removed to show the interior of the bed-frame. Fig. 6 is a detail of the end of one of the wedges. Fig. 7 is a fragmental sectional detail illustrating the hinge. Line 7 7, Fig. 2, indicates the line of section.

A indicates the bed, provided with antifriction cross-bars *a* for sustaining the wedges *B B'*, which are provided to operate the bed-plate *C*, upon which the sensitized-metal plate is to be laid for printing.

c, c', and c'' indicate antifriction wedge-bearing cleats which sustain the bed-plate *C*. These cleats are fastened to the under face of the bed-plate and rest transversely upon the wedges and increase in thickness in cross-section proportionately to the wedges, so that the bed-plate is held level by the cleats resting upon the wedges.

D D' are screws which screw through one end of the bed-frame *A* and are connected, respectively, with the wedges to serve as means to operate the wedges to raise or lower the bed-plate *C*.

E indicates the plate-glass-carrying or transparency frame, hinged to the bed-frame at one edge by hinges *F*, so as to open like a lid. The glass-carrying frame is pivoted to the hinges *F* by a pivot *f* to allow the glass-carrying frame to tilt transversely to the direction in which it moves on hinges *F*, and the opposite edge of the glass-carrying frame is provided with a pivot-stud *f'*, which, when the frame is closed, is held by a hasp *G*, which is provided with a hole *g* to fit upon the pivot-stud, and thus form, with the pivot *f* of the hinge, on the opposite edge of the transparency-frame *E* a pivotal support for the frame *E* to allow it to tilt endwise on an axis transverse to the axis of the wedges *B B'*, thus to adjust itself with relation to the bed-plate, which is raised or lowered by the movement of the wedges.

f'' indicates a pivot-plate fastened to one edge of the frame *E* to hold the pivot *f*.

f''' indicates a hinge-carrying pivot-plate fastened to the hinges *F F* and connected by the pivot *f* with the frame-carrying pivot-plate *f''*, thus to pivot the plate *f''* and the hinges *F F* together.

It is to be noted that the axis of the pivots *f f'* is approximately in the plane of the contact-surface of the transparent plate, thus to avoid any swinging movement of such surface which might displace the negative and cause slurring of the film.

H H' are antifriction-plates to receive the endwise thrust of the bed-plate when it is operated upon by the wedges.

I is a screw-bearing plate fastened to the end of the wedge to receive the thrust of the screw.

J indicates a strap provided with a tapering vertical slot *j* and fastened to the end of the wedge.

The thrust end of the screw is provided with a head *d*, and the larger end of the slot *j* is large enough to allow the head to pass therethrough, while the smaller end of the slot is only large enough to chamber the neck between the head and the body of the screw. This allows the wedge to be easily attached to and detached from the screw and inserted into and withdrawn from the frame. The narrow part of the slot is preferably uppermost, so that in inserting the screw into place the head *d* is easily inserted through the lower large end of the slot, and when the screw rests upon the cross-bars *a* the head *d* of the screw will catch against the strap when the screw is retracted and thus draw the wedge to lower the bed-plate.

K K indicate the nuts through which the screws work. Each nut *K* is firmly bolted by bolts *k* to the end of the bed-frame and rests against the inside of such frame, so that the end of the frame will sustain the thrust of the screw.

The bed-frame is made of strong wood, such as oak, and is dovetailed at the corners or otherwise constructed so that it will withstand the thrust of the screws.

L L' indicate leveling-cushions, of rubber or other suitable material, let into the bed and arranged at the opposite ends of the bed at the side to which the frame *E* is hinged. The object of these cushions is to level the frame *E* endwise, so that such frame will come down parallel with the bed-plate without liability of touching the negative unevenly.

L'' indicates a like cushion at the middle of the front of the bed for the front of the frame *E* to rest on when fully lowered.

We will now describe the operation of printing an image on a sensitized-metal plate. The bed being in position with the wedges retracted, as indicated in Figs. 1 and 3, the plate-glass frame *E* is thrown back, as indicated in Fig. 5, and the sensitized-metal plate *M*, Fig. 4, is placed in the bed *C* in the desired position on the bed-plate *E* with sensitive side up. Then the negative *N* is placed in the desired position upon the sensitized plate. The negative can be seen through and be accurately adjusted to the best position on the plate. Then the plate-glass-carrying frame is brought down to clamp the

sensitive plate and the negative together, and as it descends it engages the cushions LL', thus bringing the glass parallel endwise with the bed-plate. When the frame E is 5 fully lowered, it engages cushion L" and is held practically parallel with the bed. The hasp G is then clasped upon the pivot f', and the frame is then ready for the application of the pressure to produce the desired contact 10 between the plate and negative. This is done by simultaneously or alternately turning the screws D D' to force the wedges under the bed-plate, thus to force such plate up toward the plate glass E'. The frame E is held a 15 short distance, say an eighth or a quarter of an inch, more or less, above the bed-frame A by the pivots f f', so that the frame E will tilt endwise without contacting with the bed. The arrangement of the movable bed-plate 20 and pivoted plate-glass frame and the operating-wedges produces a proper parallelism between the bed-plate and the plate-glass frame when the wedges are operated.

While we desire to claim the entire combination shown, we wish it to be understood that the bed-plate may be operated by appliances other than wedges and screws without departing from the spirit of our invention.

The object in using the bars *a* and cleats *c*, &c., is to secure lightness and avoid friction. The bed-plate is made virtually wedge shape by the cleats, thus to maintain the face of the bed-plate at right angles to the path in which it is moved by the wedges. The wedges are 35 let into the cross-bars *a*, as indicated in Figs. 1, 3, and 4, so that they are held in true line with their respective screws, so as to be moved thereby without cramping.

One wedge might be used alone, but the two 40 or more wedges serve the purpose better, allowing the force to be applied with greater ease. The top of the bed-plate may be covered with any suitable padding, as is common with bed-plates in ordinary use.

Now, having described our invention, what 45 we claim as new, and desire to secure by Letters Patent, is—

1. The combination of the bed, the movable bed-plate mounted on the bed and adapted to 50 receive a sensitized-metal plate and negative and to move them through a determined path; a movable transparent plate adapted and arranged to be fastened in the said path through which the bed-plate is adapted to move the negative; means for fastening the transparent

plate in such path; and any suitable means adapted and arranged to move the bed-plate in such path and to push it up sufficiently to force the sensitized plate against the negative, and the negative against the transparent 60 plate, and to thus cause perfect contact between the sensitized plate and the negative after the negative has been placed on top of the sensitized plate and the transparent plate has been fastened in place to intercept and 65 hold the negative when the sensitized plate is forced up against it.

2. The combination of the bed; the plate-glass frame provided with the glass plate and hinged and pivoted at one edge to one side of 70 the bed and provided on its other edge with a pivot-stud; a hasp fastened to the bed and provided with a hole to fit upon the pivot-stud; the bed-plate arranged in the bed to move toward and from the glass; and means 75 for forcing the bed-plate toward the glass.

3. The contact-printing frame provided with the bed and with the plate-glass frame hinged and pivoted to the bed and provided with the leveling-cushions arranged to contact 80 with the plate-glass frame on opposite sides of the pivot thereof to level the same when it is closed down toward the bed.

4. The combination of the bed; the plate-glass frame; the hinges fastened to the bed; 85 the frame-carrying pivot-plate fastened to one edge of the frame; the hinge-carrying pivot-plate fastened to the hinges; and the pivot connecting the hinge-carrying pivot-plate and the frame-carrying pivot-plate. 90

5. The contact-printing frame set forth comprising the bed; the plate-glass frame provided with the glass plate; the frame-carrying pivot-plate fastened to one edge of the frame; the hinge fastened to the bed; the 95 hinge-carrying pivot-plate fastened to the hinge; the pivot connecting the frame-carrying pivot-plate with the hinge-carrying pivot-plate; the pivot-stud arranged on the opposite side of the frame; the hasp fastened to 100 the bed and arranged to fit the pivot-stud; the bed-plate arranged in the bed to move toward and from the glass; the wedge arranged to move the bed-plate; and means for operating the wedge.
